UNITED STATES PATENT OFFICE

BRUCE HAMER LEESON, OF TYNEMOUTH, ENGLAND, ASSIGNOR TO A. REYROLLE & COMPANY, LIMITED, OF HEBBURN-ON-TYNE, ENGLAND, A COMPANY OF GREAT BRITAIN

ELECTRICAL REMOTE CONTROL SYSTEM

Application filed June 18, 1927, Serial No. 199,346, and in Great Britain July 29, 1926.

This invention relates to an electrical system for the remote control of a number of switches or other apparatus and is more especially applicable to the remote control of electric power substations from a central station. Thus for example there may be a number of feeders leading from a substation each controlled by a circuit-breaker and the system according to the invention may be used for the selective control of such circuit-breakers. Or again the system may be employed for controlling a sequence of operations, such as would be required in starting up semi-automatic substation apparatus and connecting it to a load circuit.

Generally speaking, the invention has for its object to provide a simple system wherein an operator at a central station can obtain immediate information as to the condition of apparatus at a substation and can operate such apparatus at will.

In the remote control system according to the invention a selector device at the substation is caused by currents transmitted from the central station to select an individual switch or other apparatus and to give an indication at the central station of the condition thereof, and means are provided whereby the selecting movement of the selector device causes circuits to be left free for the immediate transmission of current from the central station for the operation of the selected switch or other apparatus.

Preferably a step-by-step movement is imparted to the selector device to cause the successive completion of circuits associated respectively with the individual switches or other apparatus. These circuits may be such that after each movement of the selector device an indication is given at the central station of the condition of an individual switch, whilst current for operating such switch (if desired) can be immediately transmitted from the central station. Means are also preferably provided whereby, if such operating current is transmitted, a further indication is given at the central station immediately the operation of the selected switch is completed.

A further feature of the invention relates to the apparatus employed for giving the desired selective indication of the condition of the substation switches. According to this further feature of the invention corresponding movements are imparted to two devices, one of which at the substation constitutes a selector device acting to cause the successive completion of indicating circuits associated respectively with the individual switches or other apparatus, whilst the other constitutes a selection-indicating device disposed at the central station for the purpose of giving an indication as to which of the indicating circuits has been completed by the selector device, a second indicating device being provided at the central station which is operated by the indicating circuits to give an indication of the condition of the selected switch. The two correspondingly moved devices are preferably each of the rotary type, and the selector-device may have a step-by-step rotational movement imparted to it by a solenoid-actuated ratchet wheel, the circuit to the solenoid being controlled by a hand-operated switch (for example of the push-button type) at the central station. The selection-indicating device may have a similar and simultaneous step-by-step rotational movement imparted to it by a solenoid-operated ratchet wheel, the two solenoids being connected in series with one another. With this arrangement owing to the practical difficulty of constructing two solenoids which

will respond accurately to the same value of operating current, it may in some cases be desirable to provide means for ensuring correct and simultaneous rotation of the two devices. To this end the first movement of the plunger of each solenoid may be arranged to short-circuit a resistance in the common controlling circuit or otherwise to increase the magnitude of the controlling current. Thus as soon as one plunger begins to move the controlling current will be automatically increased, thereby ensuring that the other solenoid will also respond, and as soon as the second plunger begins to move there will be a further increase in the controlling current which will ensure that both

plungers will complete their movement and operate their ratchet wheels.

It will generally be desirable to provide means whereby, when a change takes place in the condition of any of the controlled switches or other apparatus (other than as a result of operation from the central station), an alarm is given at the central station. This may be effected by means of an alarm relay in the substation which is energized when such a change occurs and acts to complete a circuit to an indicating or alarm device in the central station, such device preferably being that which gives an indication of the condition of a selected switch. This alarm relay is preferably rendered ineffective during operation of the selector device, and means may be provided whereby an alarm which should have been given during such operation is stored up until the operation is completed.

The transmission of currents for the operation of the selector device and for the operation of a selected switch or other apparatus is preferably controlled by means of two hand-switches at the central station.

The invention may be carried into practice in various ways but one convenient arrangement according thereto is illustrated by way of example in the accompanying drawings. This arrangement will, for convenience, be described with reference to the remote control from a central station of a number of circuit-breakers each controlling a feeder leading from the substation, although it will be appreciated that the system is applicable to the control of other apparatus and is of such a nature as to render it particularly suitable also for the control of a sequence of operations such as is required for the starting-up and throwing on to load of semi-automatic substation apparatus.

In the accompanying drawings,

Figure 1 is a diagram showing the arrangement of the electrical circuits,

Figures 2 and 3 are respectively end and front elevations of the selection-indicating device at the central station,

Figures 4 and 5 show the device at the central station for indicating the condition of a selected circuit-breaker, and

Figures 6 and 7 illustrate the substation selector device.

In this arrangement the central station apparatus (which is indicated in the lower half of Figure 1) is connected to the substation apparatus (indicated in the upper half of Figure 1) by means of three pilot wires A A¹ A², one of which A is employed mainly for selective and indicating purposes and may be referred to as the "selective pilot", whilst the second A¹, the "execution pilot", is used for transmitting currents for operating a selected

circuit-breaker, and the third A² is a common return circuit.

The apparatus at the central station comprises broadly a selection-indicator, an alarm indicator and two hand-operated switches of the push-button type, the first for selective and indicating control and the second for execution control.

The selection-indicator (see Figures 1, 2 and 3) consists of a polygonal drum B bearing indications on its various faces corresponding to the circuit-breakers to be controlled, such indications being visible through a slot indicated at B¹ in the control panel. The drum B is mounted on a shaft B² carrying at one end a ratchet wheel C, having the same number of teeth as the drum B has faces. Cooperating with the ratchet wheel C is a pawl C¹ carried by a lever C² freely mounted on the shaft B², this lever being pivoted at its end to a rod C³ driven by the plunger of a solenoid D. The shaft B² also carries a locking wheel E having recesses E¹ in which engages a roller E² carried on the end of a pivoted arm E³, the roller E² being held in the recesses E¹ by a spring E⁴ for the purpose of ensuring that the indications on the drum are properly disposed with relation to the slot B¹.

The solenoid D is connected on one side to the selective pilot A, and on the other side through a resistance D¹ (part of which is short-circuited by means of contacts D² as soon as the solenoid plunger begins to move) to the normally open contacts F¹ of the selective hand-switch F. The other side of the contacts F¹ is connected to the operating coil G of the alarm indicator the other side of this coil being connected to the return pilot A². The hand-switch F is also provided with normally closed contacts F², which make direct connection through resistances F³ between the selective pilot A and the alarm coil G. Thus normally the alarm coil G is connected between the selective and return pilots through the resistances F³, but when the selective hand-switch F is depressed, the resistances F³ are cut out and the solenoid D and its resistance D¹ are substituted therefor.

The alarm indicator (see Figures 1, 4 and 5) consists of a pivoted armature G¹ operated by the coil G and carrying at its ends two indicating surfaces G² G³ respectively bearing the legends Normal and Out, the arrangement being such that when the coil G is operated the armature G¹ will lift and expose the surface G³ through a slot indicated at G⁴ in the control panel in place of the normally exposed surface G². The coil G also operates contacts G⁵ controlling the circuit of an alarm bell G⁶ energized from a battery G⁷.

The execution hand-switch H, when depressed, closes normally open contacts H¹ and thus makes a direct connection between

the execution pilot A^1 and the return pilot A^2 .

The apparatus at the substation includes, in addition to the circuit-breakers and their associated devices, a selector and three relays, 5 which may be termed the general alarm relay, the storing relay and the execution relay respectively.

The selector (see Figures 1, 6 and 7) comprises a rotary contact drum J , which may 10 be of any convenient construction but as shown is in the form of a cylinder of insulating material bearing on its surface conducting segments each of which in the appropriate drum position bridges the gap between a 15 pair of spring contact arms $J^1 J^2$. The drum J is mounted on a shaft J^3 which is driven by mechanism similar to that employed for driving the selection-indicator at the central station. Thus a ratchet wheel K mounted on 20 the shaft J^3 cooperates with a pawl K^1 carried by a lever K^2 which is driven through a rod K^3 by the plunger of a solenoid L , and the shaft J^3 also carries a locking wheel M having recesses M^1 engaged by a roller M^2 25 on the end of a spring-controlled arm M^3 .

The solenoid L is connected on one side to the selective pilot A and on the other side to a resistance L^1 , part of which is short-circuited by the contacts L^2 immediately 30 the solenoid plunger begins to move. The solenoid L is also provided with change-over contacts L^3 , referred to later. The other side of the resistance L^1 is connected to the control busbar V^1 , which together with the control 35 busbar V^2 is illustrated as energized from a source of current V . The return pilot A^2 is directly connected to the busbar V^2 . There is thus normally a complete circuit containing the solenoid L and resistance L^1 , the selective pilot A , the resistances F^3 , the alarm indicator coil G and the return pilot A^2 , but the magnitude of the current flowing in this 40 circuit is insufficient to operate either the solenoid L or the alarm indicator. When 45 however the selective hand-switch F is depressed, the solenoid D and its resistance D^1 are inserted in this circuit in place of the resistances F^3 , and the current is now large enough to operate the solenoids D and L , but 50 is still insufficient to operate the alarm indicator even after the contacts D^2 and L^2 have closed to decrease the resistance in the circuit.

The step-by-step movement of the selector 55 causes the successive closing of groups of contacts (similar to $J^1 J^2$ of Figure 7), each group being associated with one of the circuit-breakers. In Figure 1 of the drawings two circuit-breakers N and O only are shown, 60 but it will be seen from Figures 2-7 that the apparatus illustrated is capable of dealing with nine circuit-breakers. Thus the first operation of the selective hand-switch F causes the selector to step round to the first 65 position and close the three contacts $P^1 Q^1 R^1$

(Figures 1 and 7) associated with the first circuit-breaker N . The second operation of the hand-switch F causes the selector to break these contacts $P^1 Q^1 R^1$ and to close the contacts $P^2 Q^2 R^2$ associated with the second circuit-breaker O , and so on until the last operation brings the circuits back to their original condition, the selector having made one complete revolution. The first movement of the selector from its zero position also closes a 70 contact P and opens a contact Q , these contacts being common to all the circuit-breakers and not returning to their original positions until the cycle is completed. 75

The first contacts $P^1 P^2$ of each group 80 cooperate with auxiliary switches $N^1 O^1$ on the circuit-breakers to control indicating circuits containing resistances $N^2 O^2$. The auxiliary switch N^1 or O^1 is closed when its circuit-breaker N or O is open, and the arrangement is such that, when the selector moves to its first position, (assuming that the first circuit-breaker N is open) the resistance N^2 is connected across the solenoid L and its resistance L^2 , thus increasing the current flowing 85 through the selective pilot to such an extent as to operate the alarm indicator at the central station. The reduction in current in the circuit of the solenoid L due to the connecting up of the resistance N^2 is not, however, such as to prevent energization of the solenoid when the selective switch F is again depressed. The second contacts $Q^1 Q^2$ of 90 each group on the selector are in series respectively with the trip coils $N^3 O^3$ of the circuit-breakers and the third contacts $R^1 R^2$ are in series with the closing coils $N^4 O^4$. These tripping and closing circuits are also controlled by a change-over auxiliary switch N^5 or O^5 on the circuit-breaker, and on the 95 other side of the selector contacts by the change-over contacts L^3 of the solenoid L and the contacts S^1 of the execution relay S . The execution relay S is connected on one 100 side to the execution pilot A^1 and on the other side through a resistance S^2 to the control busbar V^1 . Thus depression of the execution hand-switch H energizes the execution relay S which closes its contacts S^1 . 105

Assuming now that the circuits are in the condition shown in Figure 1 with the circuit-breaker N open and the circuit-breaker O closed, depression of the selective hand-switch F will cause the selector to move to its first position and close its contacts $P^1 Q^1 R^1$, the selection-indicator simultaneously moving to display Feeder 1 through the slot B^1 in place of the normally exposed legend Alarm. Since the switch N^1 is closed, the indication circuit will now be complete and the alarm indicator G will operate to show Out through the slot G^4 . If now the operator wishes to close the circuit-breaker N , he must release the selective switch F (thus allowing 115 the contact L^3 to return to the lower position) 120

and depress the execution hand-switch H. The execution relay contacts S¹ will close and thus (since the auxiliary switch N⁵ is in its right-hand position) complete the circuit to the closing coil N⁴, which will close the circuit-breaker N. At the same time the auxiliary switch N¹ will open and will deenergize the alarm indicator G, which will thus display Normal through the slot G⁴ to give the desired indication that the circuit-breaker N has closed. It should be mentioned that the values of the various resistances are such that the release of the selective switch F to cause the contact L³ to drop does not reduce the current sufficiently to de-energize the alarm indicator G. In this connection, it is to be noted that, during the above mentioned operation of closing the circuit breaker N by releasing the selective switch F, the solenoid L and its resistance L' are shunted by the resistance N², whereas in the normally complete circuit previously referred to containing the solenoid L and the resistance L', the selective pilot A, the resistances F³, the alarm indicator coil G, and the return pilot A², the solenoid L and its resistance L' are not shunted by the resistance N². The execution hand-switch H having been released, the selective hand-switch F is again depressed to move the selector and selection-indicator to the second position. Since the circuit-breaker O is closed, the indicating circuit is broken by the auxiliary switch O¹ and the alarm indicator shows Normal. If now it is desired to trip the circuit-breaker O, the selective hand-switch F is locked in its depressed position (to maintain the contact L³ in its upper position) and the execution hand-switch H is depressed. This completes the circuit to the trip coil O³ which trips the circuit-breaker O, the alarm indicator G thus being operated to show Out. By completing the cycle an indication is obtained of the condition of all the circuit-breakers and an opportunity is afforded of operating any of them, should it be so desired, the circuits finally returning to the condition shown.

Each circuit-breaker is provided with a further auxiliary switch N⁶ or O⁶ which is so arranged that it momentarily makes and breaks a circuit when the circuit-breaker trips, but remains ineffective when the circuit-breaker closes. This switch comprises a pair of spring contacts N⁷ and N⁸ arranged so that they are momentarily bridged by the conducting bar N⁶ as the circuit-breaker opens or closes. In order to render such bridging ineffective when the circuit-breaker closes an insulated block N⁹ or N¹⁰ is arranged on one side of each of the contacts N⁷ and N⁸ so that the bar N⁶ engages with such insulated blocks when it moves past the contacts during the closing movement of the circuit-breaker but electrically connects N⁷ and N⁸ when it moves past the contacts during the

opening movement of the circuit-breaker. The circuit momentarily completed by the switch N⁶ extends from the control busbar V¹ through a resistance T¹ the operating coil T of the general alarm relay, contact N⁸, bar N⁶, contact N⁷ to the control busbar V². Thus if a circuit-breaker trips automatically, the general alarm relay T will close its contact T² and (if the selector is in its zero position with the common contact Q closed) will thus complete a circuit for holding the relay T energized and for actuating the alarm indicator G in the central station. This circuit may be traced from the control busbar V¹ through the resistance T¹, the relay T, the contact T², the contact Q, the pilot wire A, the resistance F³, the contact F², the resistance F³, the alarm indicator G, and the pilot wire A² to the control busbar V². This alarm indicator thus shows Out and rings the alarm bell G⁶, and it is then necessary for the operator at the central station to operate the selector in order to determine which circuit-breaker has tripped, and, if desired, to close it again. It should be mentioned that, if the closing of a circuit-breaker is immediately followed by its automatic tripping out again, the alarm indicator G will first indicate the closing and then the tripping so that the operator will have an immediate indication that there is some fault in the circuit concerned.

If now a circuit-breaker trips out automatically during the performance of a selecting cycle, the general alarm relay contacts T² will be cut off from the alarm indicator G owing to the fact that the contact Q is open. But the other common contact P is now closed and consequently the storing relay U is connected in parallel with the general alarm relay T between the spring contact N⁸ and the control busbar V¹. Thus the momentary operation of the auxiliary switch N⁶ or O⁶ will energize both the relays T and U, and the consequent closing of contact U¹ will complete a holding circuit for both relays, this circuit being traced from the control busbar V² through the contact U¹ and thence either through the relay U and the contact P or through the relay T and the resistance T¹ to the control busbar V¹. Nothing further will happen in this circuit until the cycle is completed, when the closing of the contact Q will complete the alarm circuit and give the desired alarm at the central station.

It will be appreciated that the arrangements more particularly described have been given by way of example only, and that the system can be modified in many ways without departing from the scope of the invention.

What I claim as my invention and desire to secure by Letters Patent is:—

1. In an electrical control system, the combination of two step-by-step devices, an elec-

- tromagnetic device having a movable member for operating each step-by-step device, means for simultaneously energizing the two electromagnetic devices for the performance of each stepped movement of the two step-by-step devices, and means whereby the first movement of the movable member of either electromagnetic device acts to increase the magnitude of the energizing current supplied to the other electromagnetic device.
2. In an electrical remote control system, the combination of two step-by-step devices to which corresponding stepped movements are to be imparted, two electromagnetic devices having movable members serving respectively to actuate the two step-by-step devices, a pilot circuit in which the two electromagnetic devices are connected in series, means for causing repeated energization and de-energization of the two electromagnetic devices whereby corresponding stepped movements are imparted to the two step-by-step devices, and means whereby on energization of the two electromagnetic devices the first movement of the movable member of each electromagnetic device acts to increase the magnitude of the current in the pilot circuit.
3. In an electrical remote control system, the combination of two step-by-step devices to which corresponding stepped movements are to be imparted, two solenoids having plungers serving respectively to actuate the two devices, a pilot circuit in which the two solenoids are connected in series, means for causing repeated energization and de-energization of the two solenoids whereby corresponding stepped movements are imparted to the two devices, a resistance connected in series with each solenoid, and means whereby on energization of the two solenoids the first movement of the plunger of each solenoid acts to short-circuit part of the associated resistance and thereby to increase the magnitude of the current in the pilot circuit.
4. In an electrical control system, the combination of two rotary step-by-step devices, a ratchet mechanism through which step-by-step movements are imparted to each device, a solenoid having a plunger actuating each ratchet mechanism, means for simultaneously energizing the two operating solenoids for the performance of each stepped movement of the two devices, and means whereby the first movement of the plunger of either solenoid acts to increase the magnitude of the energizing current supplied to the other solenoid.
5. In an electrical remote control system, the combination of two rotary step-by-step devices, a ratchet mechanism through which step-by-step movements are imparted to each device, a solenoid having a plunger actuating each ratchet mechanism, a pilot circuit in which the two solenoids are connected in series, means for causing the repeated energization and de-energization of the two solenoids whereby corresponding stepped movements are imparted to the two devices, a resistance connected in series with each solenoid, and means whereby on energization of the two solenoids the first movement of the plunger of each solenoid acts to short-circuit part of the associated resistance and thereby to increase the magnitude of the current in the pilot circuit.

In testimony whereof I have signed my name to this specification.

BRUCE HAMER LEESON.
